(57) **CLAIM**

The ornamental design for a fingertip toy block component, as shown and described.

DESCRIPTION

FIG. 1 is a front view of a first embodiment of the new design;

FIG. 2 is a back view of the first embodiment;

FIG. 3 is a left side view of the first embodiment;

FIG. 4 is a right side view of the first embodiment;

FIG. 5 is a top view of the first embodiment;

FIG. 6 is a bottom view of the first embodiment;

FIG. 7 is a perspective view of the first embodiment;

FIG. 8 is another perspective view of the first embodiment;

FIG. 9 is a front view of a second embodiment of the new design;

FIG. 10 is a back view of the second embodiment;

FIG. 11 is a left side view of the second embodiment;

FIG. 12 is a right side view of the second embodiment;

FIG. 13 is a top view of the second embodiment;

FIG. 14 is a bottom view of the second embodiment;

FIG. 15 is a perspective view of the second embodiment; and,

FIG. 16 is another perspective view of the second embodiment.

The broken lines are for the purpose of illustrating portions of the article that form no part of the claimed design.
